UNITED STATES PATENT OFFICE

106,981

DESIGN FOR AN ELECTRIC FENCE CONTROLLER CABINET

Daniel Allcott Kelly, Milwaukee, Wis., assignor to
The Prime Manufacturing Company, Milwaukee,
Wis., a corporation of Wisconsin

Application August 28, 1937, Serial No. 71,374

Term of patent 14 years

To all whom it may concern:

Be it known that I, Daniel Allcott Kelly, a citizen of the United States, residing at Milwaukee, in the county of Milwaukee and State of Wisconsin, have invented a new, original, and ornamental Design for an Electric Fence Controller Cabinet, of which the following is a specification, reference being had to the accompanying drawing, forming part thereof.

Figure 1 is a perspective view showing the front,

top and one side of an electric fence controller cabinet embodying my new design; and

Figure 2 is a perspective view showing the back, top and opposite side of the cabinet.

The bottom of the cabinet has the same appearance as the top.

I claim:

The ornamental design for an electric fence controller cabinet, as shown and described.

D. ALLCOTT KELLY.
